EDWARD T. STREET, OF BOUND BROOK, NEW JERSEY, ASSIGNOR TO THE RUBEROID CO.,
OF NEW YORK, N. Y., A CORPORATION OF NEW JERSEY

AUTOMATIC ROLL WINDING MACHINE

Application filed February 21, 1928. Serial No. 256,053.

This invention relates to a machine for cutting a web or continuous sheet of flexible fabric, particularly prepared roofing material, into pieces of measured length, and winding said pieces into rolls.

Prepared roofing materials, as commonly made, are composed of a layer of roofing felt saturated with bituminous compositions, and surfaced on one or both sides with a harder bituminous composition. In some cases either one or both of the surface coatings are faced with particles of mineral matter. The material is generally marketed in roll form, each roll containing approximately 108 sq. ft. of material being sufficient to cover one "square", or 100 sq. ft., of roof surface, allowing for the proper amount of lap at the joints. The material is made in various weights, usually ranging from about 35 lbs. to about 65 lbs., or even heavier, per square. The sheet is generally formed of a standard width of 36 in., although other widths are sometimes employed. In the case of material of 36 in. width, the unwound length of the roll is about 36 feet.

By reason of the size, weight, and nature of the material considerable difficulty has been experienced in devising a machine that would successfully handle the product and wind it automatically into rolls.

My invention provides a machine that is adapted to operate upon a web of prepared roofing material, and at each cycle of its operation, to measure a length of the material, cut the measured length, wind said length into a roll, and deliver the roll.

Other and further objects of the invention will appear from the following description thereof. It is to be understood, of course, that modifications in the details of construction and arrangement of parts may be made without departing from the scope of my invention.

A preferred embodiment of the machine is shown in the drawings in which:—

Figure 1 is a conventionalized side elevation of the machine showing the driving shaft and driving mechanism.

Fig. 2 is an intermediate sectional elevation taken on the line 2—2 of Fig. 4.

Fig. 3 is a side elevation of the opposite side of the machine.

Fig. 4 is a plan view.

Fig. 5 is a transverse vertical section on the line 5—5 of Fig. 2. 55

Fig. 6 is a transverse vertical section on the line 6—6 of Fig. 2.

Fig. 7 is a transverse vertical section on the line 7—7 of Fig. 2.

Fig. 8 is an enlarged sectional view of the double-acting spring trip in one extreme position. 60

Fig. 9 is a view of the same in the opposite extreme position.

Fig. 10 is a transverse vertical section on the line 10—10 of Fig. 4, showing an end view of the roll forming mechanism. 65

Fig. 11 is a detailed view of the mechanism for moving the feed rolls into and out of feeding relation. 70

Fig. 12 is a detailed view of the operating cam and associated parts for swinging the arms 17—18.

Fig. 13 is a detailed view of the operating cam and linkage for tripping the spring trip in its reverse direction. 75

Similar reference characters indicate similar parts throughout the several views.

The framework of the machine comprises two sidepieces 1 and 2 joined together by a crosspiece 3. At one end of the frame is mounted a roll 4 that guides the web A into the machine. 80

Referring now particularly to Fig. 2, it will be seen that two pairs of feed or draw rolls 5—6 and 7—8 are supported transversely on the framework. These feed rolls are driven continuously but operate to feed the web intermittently so that during each cycle of operation a measured length of the material is carried forward. Intermediate the feed roll pairs is a measuring roll 9 over which the web travels thereby rotating said roll. A presser roll 10 is positioned above the measuring roll to hold the web in surface contact with the latter. At either end of the feed roll pairs is a clamp, each, respectively, comprising a fixed member 11—12, and a vertically movable member 13—14. Said clamps serve to hold the web fast during the period when

85

90

95

100

the feed is inoperative. Adjacent the clamp 12—14 is a cutting mechanism which includes a fixed transverse blade 15 and a vertically reciprocating blade 16 by which the web is severed transversely so as to cut off the measured length. The cutting mechanism is timed to operate at about the moment when the feed rolls are released from contact with the web and the clamps are fastened thereon.

- 10 The releasing of the feed rolls, fastening of the clamps, and downward movement of the cutting knife are controlled by certain devices whose actuation is effected by the rotation of the measuring roll 9. These devices, which are hereinafter more fully described, include the double-acting spring trip illustrated in detail in Figs. 8 and 9 of the drawings.

15 The machine is so designed that the linear rate of feed of the material, caused by the feed rolls 5—6 and 7—8 is somewhat faster than the rate at which said material is rolled up by the roll forming wheels, thus producing slack C. To accommodate the slack the 20 machine is provided with two series of alternately disposed swingable arms 17 and 18, which arms, when swung into horizontal position, form a skeleton platform over which the advancing edge of the material is fed 25 into the roll forming mechanism. Any suitable means may be provided for swinging said arms in properly timed relation to the cycle of operation of the machine. One form of such means is shown in the drawings and 30 is described hereinafter.

35 The mechanism for forming the rolls B comprises a plurality of series of alternately disposed wheels 19, 20, 21, and 22 by and between which each length of material is 40 rolled up into a separate roll. These wheels are driven to rotate continuously but at a slower rate of peripheral speed than the peripheral speed of the feed rolls 5—6 and 7—8. The wheels 19 and 20 are mounted on trans- 45 verse shafts 23, 24 which are journaled in bearings in the sidepieces 1, 2, of the frame, while the wheels 21 and 22 are mounted on shafts 25, 26 journaled in bearings in the side-pieces of a carriage 27. The carriage 50 27, which is provided with a counter weight 28, is mounted on rollers 29 that are connected together by straps 30 and ride on the side frame members so that carriage may be moved freely endwise.

55 In forming the rolls B, the advancing edge of the material is led into the roll forming space between pairs of fixed guides 31 and 32. The outer ends of the upper guide members 32 are curved upward and their inner 60 ends are enlarged and formed with concave faces 33. The guides 32 are positioned above certain of the wheels 19 and between the two adjacent wheels 20. Sufficient space is allowed between the peripheries of said wheels 65 19 and the bottoms of the guides 32 to per-

mit of passage of the material into the roll forming space. The concave faces 33 of the ends of the guides 32 serve to aid in directing the advancing edge of the material in a curvilinear path at the beginning of the 70 formation of the roll.

To assist in feeding the material into the roll forming mechanism, the machine is provided with auxiliary feed roll pairs 34. These rolls are mounted on transverse spindles 35 and are geared together, as at 36, to rotate at the same peripheral speed as the roll forming wheels 19, 20, 21, and 22.

As the roll B increases in diameter the carriage 27 is gradually pushed back by the increased bulk of the roll. The two sides of the carriage are cross connected, to assure of their uniform movement, by a crossrod 37 carrying a pinion 38 at each end, which pinions engage with racks 39 fastened to the frame sidepieces and with racks 40 secured to the sides of the carriage. When the roll B has been completely formed, the carriage 27 is positively moved back a further distance, by means of mechanism hereinafter described, so as to provide an opening through which the completed roll will be delivered or drop out of the machine, after which the carriage is returned to its initial position ready to form a new roll on the succeeding cycle of operation. If desired, any suitable form of conveyor may be provided to receive the rolls as they are discharged from the machine.

60 The continuously rotating parts of the machine, comprising the feed rolls 5—6, 7—8, and the roll forming wheels 19, 20, 21, 22, are driven by a shaft 41 which extends lengthwise of the machine and is provided with a driving pulley 42 as seen in Fig. 1. The driving shaft is journaled in fixed bearings 43, 44 secured to the frame side piece 1, and in a sliding bearing 45 fixed to the movable carriage 27. Fixed to said shaft are two bevel gears 46, 47, and splined thereto is a third bevel gear 48. Gear 46 meshes with a bevel gear 49 carried on a stub shaft journaled in the frame piece 1, as shown in Fig. 7. This stub shaft also carries a gear 50 that meshes with the gears 51 and 52 which rotate the lower feed rolls 5 and 7, respectively. The latter gears engage with gears 53, 54 that turn the upper feed rolls 6 and 8. Gear 47 engages with a bevel gear 55 which, through an intermediate gear 56, turns the gears 57, 58 that rotate the shafts 23, 24 upon which the series of roll forming wheels 19 and 20 are mounted. In the embodiment illustrated, the intermediate gear 56 also drives a pinion 59 by which the feed rolls 34—34 are rotated. The third bevel gear 48 similarly engages a gear 60, and through the train of gears 61, 62, and 63, continuously rotates the wheels 21 and 22 throughout the 115 120 125 130

reciprocating movements of the carriage 27 on which said wheels are mounted.

At the left hand end of shaft 23 (see Fig. 3) is a gear 64. This gear meshes with a gear 65 mounted on a stub shaft 66 which is journaled in the frame side piece 2, as shown in Fig. 10. The stub shaft 66 also carries a smaller gear 67 which, through the gear pair 68 and 69 turns the gear 70. The gear ratio and relationship of the parts is such that the gear 70 makes one complete revolution in each cycle of operation of the machine.

71 is a link chain carrying a lug 72, which chain is driven by a sprocket 73 secured to the end of the rotating shaft 66. The opposite end of the chain is carried on a sprocket 74 which is adjustably mounted in a bearing 75 so as to take up any slack. Below the chain, and disposed in the path of the lug 72, is a member or abutment 76 which projects from the side of the carriage 27. If desired this member may be adjustable lengthwise of the carriage. The lower portion of said member is formed with a sleeve 77 that slides longitudinally on a horizontal rod 78 supported on the frame sidepiece 2. The lug 72 is so positioned and the rotation of the chain is so timed that said lug will engage the abutment 76 when the roll B is completely formed, thereby positively moving the carriage 27 rearwardly a sufficient distance to permit the roll B to drop through the enlarged space which is thus formed between the series of wheels 19 and 21. When, in its movement with the chain, the lug becomes disengaged from the abutment, the carriage 27 is quickly returned to its initial position by means of the spring 79 and the counterweight 28. Nuts 80 are provided to afford adjustment of the tension of the spring.

I shall now proceed to describe the mechanism for swinging the arms 17 and 18, a detailed view of part of which mechanism is shown in Fig. 12. This mechanism is timed to swing the arms into horizontal position after the measured length has been completely wound up, and to remain in such position a sufficient length of time to permit the freshly cut edge of the succeeding length to be fed into the roll forming mechanism over the level surface thus formed. During the formation of the roll B, said arms 17 and 18 are swung downwardly to accommodate the slack C, as hereinbefore stated. Operation of this mechanism is controlled by a cam 81 fixed to a shaft 82 which rotates continuously with the gear 70. Bearing on the cam is a follower 83 which is carried on an arm 84 having one end pivoted to a fixed support 85 and its opposite end pivoted to a slotted yoke 86. The yoke has a downward extension 87 formed with a tapered lower end 88, which taper is forced against the face of a roll 89 by a spring

90, as seen in Fig. 10. This construction provides a frictional shock absorber that takes up the jar when the follower rides off the high point of the cam and the arms 17, 18 are accordingly lowered. Extending upward from the yoke is a rod 91, and extending outward from the rod is a slide 92 in which the upper end of a flexible strap 93 is adjustably secured. The lower end of said flexible strap is fastened to, and wrapped around, a wheel 94. The wheel 94 is fixed to an end of the shaft 95 carrying the arms 17, which shaft extends through the slot in the yoke 86. It will be apparent that rotation of the cam 81 will raise the yoke 86, thus causing the flexible strap 93 to become partially unwound from the wheel 94 and thereby turning the wheel contra-clockwise. This turning motion of the wheel raises the arms 17 to horizontal position. Upon downward movement of said arms, the flexible strap 93 is again wound around the wheel 94. Fixed to the shaft 95 is a pulley 96 which is connected by a crossed belt 97 with a companion pulley 98 on the shaft 99 that carries the arms 18. Attached to shaft 99 is a pulley 100 carrying a counterpoise 101. By the arrangement just described, any movements of the arms 17 will produce corresponding movements of the arms 18.

The mechanism for reciprocating the knife 16 includes a rock-shaft 102 having fixed thereto two parallel arms 103, one at each side of the machine, to which the knife support 104 is pivotally fastened by links 105. The knife blade 16 is detachably secured to the support 104, which support is guided for vertical movements in slides 106. The arm 103 at the left hand side of the machine, see Fig. 3, has an extended end 107 that engages with the spring detent or catch 108 to hold the knife in its raised position. When this detent is released, by mechanism hereafter described, the knife will descend upon and cut the web. At one end of the rock-shaft 102 is a rocker-arm 109, and hanging loosely on said shaft is a swingable lever-arm 110. Said lever-arm is formed intermediate its ends with a sleeve 111, and is pivotally connected at its lower end, by a connecting rod 112, with the continuously rotating gear 70. Supported to slide lengthwise in the sleeve 111 is a rod 113 having one end pivotally connected to the lower end of the rocker-arm 109. A spring 114 is coiled around the opposite end of rod 113, the ends of which spring bear against the face of the sleeve 111 and the adjusting nuts 115, respectively. Obviously, as the hanging lever arm 110 is connected with the gear 70, it will swing toward said gear during half of each revolution and away from the gear during the other half. Now as the detent 108 holds the knife 16, and with it the rocker-arm 109, stationary until released, the forward swinging movement of the lever-

arm 110 will tend to compress the spring 114 against the nuts 115 so that when the detent is released said spring will expand against its opposite abutment 111, thereby assisting in causing the blade 16 to descend quickly. During the return swinging movement of the lever-arm 110, the sleeve 111 bears against the rocker-arm 109 thus positively raising the knife 16 to its initial position. In the meantime, the detent 108 has been returned to position to engage the end 107 of arm 103 so as to again hold the knife 16 stationary until the succeeding cycle of operation.

Movement of the knife detent 108, as well as release and engagement of the feed rolls and clamps, are effected by the double acting spring device shown in detail in Figs. 8 and 9. This device comprises a bar 116, preferably circular in cross-section, having its middle portion 117 of reduced diameter thus forming shoulders 118 and 119 at the ends of said portion. The bar is pivotally supported at its ends by two rocker-arms 120 and 121 so that it may move bodily endwise in either direction. Endwise movement in one direction is controlled by a catch 122 which is adapted to engage an end of the rocker-arm 120 and is limited by an adjustable stop 123. Similarly, endwise movement in the opposite direction is controlled by the catch 124 and is limited by the stop 125. Mounted to slide freely lengthwise on the reduced portion of the bar are two collars 126 and 127 between which is located a coiled spring 128. Surrounding the collars and spring is a casing comprising a tube 129 having heads 130 and 131 threaded therein at both ends, which casing is independently movable lengthwise relative to the bar 116. The casing is connected with the gear 70, as seen in Fig. 3, by a connecting rod 132, acting through the lever 110 and connecting rod 112, so as to move to and fro once for each revolution of said gear. In other words, movement of the casing is continuous throughout the operation of the machine, while movement of the bar 116 is periodic.

Referring now to Fig. 8 it will appear that as the casing moves from right to left, the casing head 130 presses against the collar 126 and slides said collar, together with the spring 128 and collar 127, to the left thus compressing the spring against the collar 127, which collar is held immovable by engagement with the shoulder 119. In said figure the casing is shown in its extreme left position, and the other parts are shown in their positions just before the catch 122 is tripped or released. Now the moment said catch is released, the spring 128 will expand thereby driving the bar 116 to the left against the stop 123 and thus rocking the two arms 120 and 121 from right to left. On the return movement of the casing the operation of the

parts is reversed so that when the catch 124 is released the arms 120 and 121 will rock from left to right.

Rocker arm 120 is secured to a transversely extending rock shaft 133, and arm 121 to a transverse rock shaft 134. Fixed to shaft 134 is an upright arm 135 which carries at its end the knife blade detent 108. When said shaft is rocked, the detent is moved away, permitting the knife to descend.

Referring particularly to Figs. 2, 4 and 5, the rock shaft 134 carries two arms 136 which are attached by links 137 to the movable clamps member 14. The links 137 are preferably forked at their upper ends and formed with slots 138 in their sides at the point of attachment to the arms, as seen in Fig. 2, so as to permit a certain amount of vertical free play between the links and the arms. The member 14 is guided for vertical movement by two rods 139, one fixed to each end of said member, which rods slide in sleeves formed on the fixed clamp member 12. Coiled around the lower end of each rod is a spring 140 which may be adjusted by an adjusting nut 141. The movable clamp member 13 is similarly attached to arms 142 on rock shaft 133. During progression of the web said clamp members are held out of contact with the web, but when the feed is intermittent the clamps are closed down upon the web.

To provide for intermediate feed of the web the feed rolls are so mounted that the rolls of each pair can be moved toward and away from each other. Referring to Figs. 6 and 11, for this purpose the ends of the shafts 143 of the lower feed rolls 5 and 7, and of the shafts 144 of the upper rolls 6 and 8, are journaled eccentrically in movable cylindrical bearings 145, 146, respectively, which bearings are mounted in the frame side pieces 1 and 2. Fastened to each bearing 145 is a strap 147, and to each bearing 146 a strap 148. The straps are connected by a linkage 149 to the arms 150 and 151 fixed to the rock shafts 133 and 134, respectively. On references to Fig. 11, which shows the parts in feeding position, it will be seen that swinging movement of the rocker arms 150, 151, from right to left will turn the bearings 146, 147 so as to separate the two feed rolls of each pair and thus intermit the feed. It should further be observed that the arms 136 and 142, carried on said rock shafts, are simultaneously depressed to fasten the clamp members 13, 14 on the web.

At one end of the shaft 152 of the measuring roll 9 is a worm 153 which engages with a worm wheel 154, as seen in Fig. 7. The relationship of the measuring roll and worm wheel is such that said wheel will make one complete revolution for each given length of material fed over the measuring roll. The worm wheel carries a pin 155 that is arranged

to engage the free end of the bent lever 156, at the completion of each revolution, so as to slide the collar 157 outwardly on the shaft 152. The collar 157 carries a finger 158 which, on the outward movement of the collar, operatively engages the dog 159 so as to trip the latter and release the catch 122. This releases the double acting spring devices, shown in Fig. 8, for movement in one direction and causes operation of the mechanisms that separate the feed rolls, fasten the clamps, and drops the cutting knife.

The reverse action of these mechanisms is effected by releasing the catch 124 when the spring device is in the position shown in Fig. 9. The release of said catch is controlled by a cam 160, shown in detail in Fig. 13, which cam is fixed to the shaft 82 of the gear 70. A cam follower 161 bears on said cam and is connected by links 162 and 163 with a bell crank 164 that carries the catch 124.

In threading the web through the machine it is necessary to temporarily lift the pressure roll 10, separate the feed rolls and raise the movable clamp members 13 and 14, so as to permit passage of the web. The pressure roll 10 is supported at its ends on swingable arms 165, which arms are each pivotally attached at one end to a support 166 extending inward from the frame side pieces 1 and 2. The other ends of said arms are connected by links 167 to a spindle 168 provided with a lever or handle 169 by which said spindle may be turned so as to raise the roll 10. A second lever or handle 170 is provided to separate the feed rolls. This handle is attached to a spindle 171 to which are fixed two arms 172 each operatively connected at its lower end to one of the linkages 149. On pressing down the handle 170, the arms 172 are swung from right to left thereby separating the feed rolls. As this motion also automatically closes down the clamps 13 and 14, means are provided whereby said clamps may be raised independently. These means comprise cams 173 mounted on spindles 174 provided with handles 175. On turning the handles the cams operate to lift the rods 139, thus raising said clamp members.

50 What I claim is:

1. In a machine of the character described, means for measuring a length of web, web feeding means, means adapted to operate said web feeding means intermittently to advance a length of web at each operation, means for cutting off said intermittently fed lengths successively, means for clamping the web during its periods of rest, means for automatically controlling actuation of the feeding, the cutting, and the clamping means, said controlling means being governed by operation of the measuring means, and means for winding each of said lengths into a roll, said winding means comprising a plurality of rotating

members between and by which the material is rolled up.

2. In a machine of the character described, web feeding means comprising two pairs of feed rolls, the rolls of each pair being movable into and out of contact with the web to feed a measured length at a time, a measuring roll located between the pairs of feed rolls and rotated by contact with the traveling web, and means actuated by the measuring roll 70 for moving the feed rolls out of contact with the web when a measured length of the web has been fed.

3. In a machine of the character described, web feeding means comprising feed rolls movable into and out of contact with the web to advance the web a measured length at a time, a vertically movable cutter operative to cut off said lengths successively, a measuring roll, a double acting spring trip device operative to control the movements of the feed rolls and the operation of the cutter, means actuated by a prescribed number of revolutions of the measuring roll to trip the spring device in one direction so as to release the feed rolls and to permit the cutter to fall, means for positively raising the cutter, a rotating cam shaft, a cam fixed to said shaft, means actuated by the cam to trip the spring device in the opposite direction so as to reset 90 the feed rolls in contact with the web and to hold the cutter in its raised position, and means for winding each length into a roll.

4. In a machine of the character described, feeding means comprising feed rolls movable into and out of contact with the web to advance the web a measured length at a time, clamping means comprising clamp members movable into and out of contact with the web to clamp the web during its periods of rest, a vertically movable cutter operative to cut off said lengths successively, a measuring roll, a double acting spring trip device operative to control the movements both of the feed rolls and the clamps, and also to control operation of the cutter, means actuated by a prescribed number of revolutions of the measuring roll 100 to trip the spring device in one direction so as to release the feed rolls, engage the clamps, and permit the cutter to fall, means for positively raising the cutter, a rotating cam shaft, a cam fixed to said shaft, means actuated by the cam to trip the spring device in the opposite direction so as to reset the feed rolls 110 in contact with the web, release the clamps, and hold the cutter in its raised position, and means for winding each length into a roll.

5. In a machine of the character described, web feeding means including a pair of feed rolls having parallel axes, each of said rolls being journaled eccentrically in cylindrical bearings which bearings are mounted to turn in fixed supports, and means for periodically turning the bearings first in one direction to bring the feed rolls into contact with the web 125 130

so as to feed a given length and then in the opposite direction to intermit the feed.

6. In a machine of the character described, a framework, web feeding means mounted on the framework, means adapted to operate said web feeding means intermittently to feed a measured length of the web with uniform velocity at each operation, means for cutting off said lengths successively, winding means carried on the framework in spaced relation to the feeding means for winding each length into a roll, a plurality of swingable arms adapted in one position to bridge the space between the feeding and the winding means so as to provide a support on which the advancing edge of the web travels towards and into the winding means, and in another position to afford a gap in which the slack that accumulates during part of the formation of each roll hangs in a loop, and means of so swinging said arms in timed relation to the travel of the web.

7. In a machine of the character described, a framework, web feeding means, means adapted to operate said web feeding means intermittently to feed a measured length of the web at each operation, means for cutting off said lengths successively, and means for winding each length into a roll comprising a carriage mounted to reciprocate on the framework and two sets of rotating members between and by which the material is rolled up, the rotating members of one set having their axes journaled in the framework and those of the other set having their axes journaled in said carriage so that as the diameter of the roll increases the latter will be moved away gradually from the relatively fixed set of rotating members, and means for positively moving the carriage back a further distance so as to discharge the completely wound roll and then returning it to its initial position.

8. In a machine of the character described, web feeding means, means for cutting the web into lengths, means for winding each length into a roll comprising a plurality of rotating members between and by which the material is rolled up, and guides for directing the advancing edge of the web into the winding means, said guides being so positioned above certain of the rotating members as to allow of passage of the web between said members and the guides, and having their inner ends provided with concave faces that direct the advancing edge of the web in a curvilinear path to form the first convolution of the roll.

9. In a machine of the character described, web feeding means comprising continuously rotating feed rolls movable periodically into and out of contact with the web and operating to feed the web a given length at a time, means for cutting off said lengths successively, a driving shaft, driving connections between said shaft and the feed rolls, means for winding each length into a roll said wind-

ing means comprising a set of continuously rotating members and a set of relatively movable continuously rotating members, the material of each roll being wound up between and by the rotating members of the two sets, driving connections between the main shaft and the fixed rotating members, and sliding driving connection between said shaft and the relatively movable rotating members.
